ORNAMENTED ARTICLE AND METHOD OF
MAKING THE SAME

Sylvan M. Straus, Gloversville, N. Y.

Application October 26, 1935, Serial No. 46,905

3 Claims. (Cl. 2—278)

My invention relates to a new and improved ornamented article of manufacture, and to a new and improved method of making the same.

One of the objects of my invention is to decorate various articles of manufacture, such as gloves, handbags, shoes and the like, it being understood that the invention is not limited to the decoration of any particular material or of any particular article of manufacture.

10 Another object of my invention is to provide an ornamented article having an imitation button effect.

Another object of my invention is to provide a very simple and efficient method for producing said imitation button effect, whereby it is unnecessary to perforate the material which is being decorated.

While the drawing illustrates the invention as being applied to gloves, this is merely for purposes of illustration.

Other objects of my invention will be set forth in the following description and drawing, which illustrates preferred embodiments thereof, it being understood that the above statements of the 25 objects of my invention are intended to generally explain the same without limiting it in any manner.

Fig. 1 is a perspective view showing the invention applied to a glove.

30 Fig. 2 is a perspective view showing a different embodiment of the invention, as applied to a glove.

Fig. 3 shows how a supplemental member is cemented or otherwise connected to one face of 35 a sheet of material which is to be decorated. In this view, part of the representation of the supplemental member has been cut away, in order to illustrate the assembly more clearly.

Fig. 4 is a partial top plan view of the embodiment illustrated in Fig. 1, showing the button effect in greater detail.

Fig. 5 is a partial top plan view of the embodiment shown in Fig. 2.

Fig. 6 is a sectional view on the line 6—6 of 45 Fig. 4.

Fig. 7 is an enlarged detail bottom plan view illustrating the stitch which is used in securing the imitation button effect.

Fig. 8 is a sectional view on the line 8—8 of 50 Fig. 5.

Referring to Fig. 3, this shows a piece of material 10, which is to be decorated. Said material may be leather, a woven or knitted fabric or the like.

55 A supplemental member 13, which may be made

of felt, or any other suitable material, is connected to the inner side of the material 10, by means of an adhesive 14, or in any other suitable manner. The supplemental member 13 is preferably flexible or bendable, but it may be 5 made of rigid material if desired, and I do not wish to be limited to any particular material for making the supplemental member 13.

In the embodiment shown in Figs. 1 and 4, a series of separated supplemental members 13 are 10 thus connected to the inner side of the material 10. It is not absolutely necessary in all cases to connect the supplemental members 13 to the member 10, by means of adhesive or the like, but this is preferred, as this connection facilitates 15 the stitching operation which is used for completing the imitation button effect.

As shown in detail in Figs. 6 and 7, I prefer to use a lock stitch. This stitch may be made by any suitable machine or by hand. If the stitch 20 is made by means of a machine, I prefer to employ a needle thread 15, which is of any ordinary type, such as cotton or silk or the like. This needle thread 15 is relatively non-stretchable, save to the extent that ordinary sewing thread 25 is stretchable to a certain extent.

The supplemental or bobbin thread 16, is elastic. The bobbin thread 16 may be made of elastic rubber, or it may be made of covered rubber thread, of the familiar type known as "lastex". 30 This type of thread consists of an elastic rubber core, which is covered with one or more helical windings of cotton yarn, silk yarn or the like. This type of thread is very stretchable and elastic, and it can be made quite thin. The bobbin thread 16 is preferably maintained under tension, while it is being laid around the periphery of the supplemental member 13. The bobbin thread 35 16 is maintained in its tensed condition, by means of the needle thread 15.

Fig. 7 shows how the bobbin thread 16 is passed through the needle loops 15a of the needle thread 15. These needle threads 15a engage the elastic thread 16 with sufficient frictional hold, so as to maintain the material 10 in gathered form 45 around the edge of the supplemental member 13. Hence, in the final article, the thread 16 may be under little or no tension, or it may be under tension and to any desired extent.

The result of the use of the elastic thread, is 50 to pucker or gather the flexible material 10, as illustrated in Fig. 6. A cup-shaped recess 17 is thus formed in the fabric, and the supplemental member 13, which has some resilience or springiness, is bent so that its original flat disc shape 55

is changed into a curved or arch shape. The member 13 preferably has sufficient resilience, so that it tightly abuts the inclined side walls of the recess 17, as shown in Fig. 6.

5 The result is to produce an imitation button effect, at separated points of the material 10, as illustrated in Fig. 4. I do not wish to be limited to any particular shape of the supplemental members 13, because they could be elliptical or have 10 any desired shape. Neither do I wish to be limited to the particular type of stitch which is disclosed herein, as the preferred embodiment.

In the modification illustrated in Figs. 2, 5, and 8, the same method is essentially used, save 15 that the stitch is continued along straight lines between the separated supplemental members 13, so as to form gathers or pleats 18 in the fabric, between the covered supplemental members 13.

I have described preferred embodiments of my 20 invention, but it is clear that numerous changes and omissions could be made without departing from its spirit. The drawing is substantially to scale.

The glove is designated by the reference letter 25 G.

The claims for the article of manufacture are not to be limited to any particular method of manufacture.

If the supplemental member or insert is rigid, 30 it fills the recess in the flexible base material. Said base material is so thin and flexible that it does not have a predetermined or normal shape. Hence the material which I prefer to employ can- 35 not be embossed so as to provide recesses of permanent shape, due to the stiffness of the material.

I do not wish to be limited to the use of stitches for gathering the material 10 so as to maintain 40 it in recessed shape. The thread 16 could be secured to the material 10 by means of an adhesive. Likewise, the use of an elastic thread is convenient for automatically gathering the material at the base of the recess, but said material could be gathered or pleated so as to form the

recess in any manner, and non-elastic material 16 could then be applied for holding the material in recessed form.

If desired, the elastic thread 16 could be connected to the fabric so as to gather the material. 5 The insert or supplemental member 13 could then be forced through the closed annulus of thread 16, into the position shown in Fig. 6. Hence the order of the steps of the method can be varied. The thread 16 may form a substantially closed 10 annulus, but I do not wish to be limited to a closed loop or annulus of thread 16.

I claim:

1. An ornamental flexible material having a recess, a bendable member located within said 15 recess and partially filling said recess, said bendable member abutting the inner wall and the side walls of said recess, and means for maintaining said flexible material in the recessed shape, said means comprising an elastic thread which is connected to said material at the base of said recess. 20

2. An ornamental flexible material having a recess, a bendable member located within said recess and partially filling said recess, said bendable member abutting the inner wall and the side 25 walls of said recess, and means for maintaining the flexible material in the recessed shape, said means comprising an elastic thread which is connected at spaced points to said material at the base of said recess, said elastic thread being 30 connected to said fabric by means of spaced thread loops which are located at the inner face of the ornamented material, said loops being connected at the fair side of the ornamented material.

3. A method of producing an imitation button 35 effect in flexible material, which consists in applying a supplemental member to one face of said material, and applying an elastic thread which is maintained under tension to said material around the periphery of said supplemental member, so 40 as to form a recess in said material in which said supplemental member is held.

SYLVAN M. STRAUS.
